ROY T. AXE, OF SYRACUSE, NEW YORK, ASSIGNOR TO OLIVER M. EDWARDS, OF SYRACUSE, NEW YORK.

TRAP-DOOR FOR RAILWAY-CAR PLATFORMS.

1,119,784.

Specification of Letters Patent.

Patented Dec. 1, 1914.

Application filed February 24, 1912. Serial No. 679,660.

To all whom it may concern:

Be it known that I, Roy T. Axe, of Syracuse, in the county of Onondaga and State of New York, have invented a certain new and useful Trap-Door for Railway-Car Platforms, of which the following is a specification.

This invention has for its object the production of a trap door for railway car platforms which is particularly simple in construction, and highly efficient and durable in use; and it consists in the combinations and constructions hereinafter set forth and claimed.

15 In describing this invention reference is had to the accompanying drawing in which like characters designate corresponding parts in all the views.

Figure 1 is a plan view of a preferable form of this trap door, contiguous parts of the platform and car structure being also shown. Figs. 2 and 3 are sectional views taken at a right angle to each other, parts being omitted in Fig. 3. Fig. 4 is a plan view of parts seen in Fig. 3, the floor being omitted.

This trap door for railway car platforms comprises, generally, a support movable about an axis, a floor carried by the support and shiftable edgewise in a direction parallel to the axis of the support, and means for shifting the floor. Usually the floor is shiftable relatively to the support and one of the shiftable engaged parts is provided with raised bearing surfaces for engaging the other, the shiftable engaged parts between the bearing surfaces being spaced apart. Preferably the major part of the floor is located on one side of the axis of its support and a marginal portion is located on the other side of such axis, and the means for shifting the floor is connected to said marginal portion. The support, as here illustrated, comprises a body 1 and leaves 2 hinged to the body and arranged with their pivotal axes extending crosswise of the axis of the body, and the floor 3 is mounted on the support above the body so that the support engages with the under face thereof.

50 The body 1 is here shown as a spring barrel journaled in bearings 4 and 5 supported by the frame of the car, a torsion spring 6 being located within the barrel and fixed at one end in any suitable manner to the bearing 4 and at its other end to the body 1.

The construction of the spring barrel forms no part of this invention and further description thereof is thought to be unnecessary.

The leaves 2, are pivoted at 7 to brackets 8 mounted on the spring barrel at points spaced apart in a direction lengthwise thereof, and are slidably connected near their free ends to the floor by pin-and-slot connections 9. The floor is secured to the support by said pin-and-slot connections 9 and by sliding bearings as metal straps or bearing members 10 secured at their ends to the under face of the floor and having their intermediate portions extending around the barrel 1. The straps 10 are so arranged as to engage the brackets 8 to limit the movement of the floor 3 in either its normal or extended position.

15 In this embodiment of my invention, the support is preferably provided with bearing surfaces located near opposite ends of the leaves 2, two of such bearing surfaces being provided near the body 1 and usually directly above the axis of the body 1, and the others at the free ends of the leaves 2. The bearing surfaces directly above the axis are provided at 11 on the brackets 8, and the bearing surfaces near the free ends of the leaves are provided at 12, around the pin-and-slot connections 9. Thus the floor and its support engage only at four points so that friction between the floor and its support and the liability of marring the under face of the floor, is reduced to a minimum.

20 Preferably the body 1 of the support is arranged along, and parallel to, the end wall 13 of the car so that the door may swing from its closed position into a vertical position at one side of the steps 14 when raised to uncover such steps.

25 The means for sliding the floor 3 edgewise relatively to its support comprises a vertical rock shaft or post 15 rising from the platform 16 and extending below the same and provided with a rock arm 17 at its lower end, and a link 18 connected by universal joints to the rock arm 17 and to the under face of the marginal portion 19 of the floor located on the opposite side of the axis 105 of the barrel 1 to that on which the major part of the floor is located. The link 18 is located beneath the platform and extends through the riser of the top step of the steps 14 and through an arc shaped slot 20 in a 110

plate 21 supported by the riser of said top step..

The rock shaft 15 is also provided with suitable handle 22 which is connected to the rock shaft 15 by a horizontal pivot 23 which permits the handle to be folded down along the shaft, as seen in Fig. 2, when not in use. When the floor is in horizontal position its free edge is supported by a suitable shoulder 24 and it is held from being raised by the torsion spring 6, by a suitable latch not shown.

My trap door is particularly adapted to be used in cars stopping at stations where the station platforms are below the level of the car platforms so that passengers boarding or alighting from, the trains must use the steps, and at stations where the station platforms are flush with those of the cars 15 and a space intervenes between the side of the cars and the station platforms. When the cars are stopping at the last-mentioned class of platforms, the doors are projected laterally slightly, to bridge the intervening 20 space between the sides of the cars and the station platforms, by operating the rock shaft 15 causing the floor 3 to slide on the bearing surfaces 11 and 12.

What I claim is:

1. In a trap door for railway car platforms, a support, a floor slidably carried by the support and shiftable edgewise relatively thereto, the support being slidably engaged with the under face of the floor and 30 one of the slidably engaged parts being formed with raised bearing faces for engaging the other of said parts, and the slidably engaged parts being spaced apart between the bearing faces, and means for shifting the floor, substantially as and for the purpose described.

2. In a trap door for railway car platforms, a support movable about an axis, a floor slidably mounted on the support and 45 shiftable edgewise in a direction parallel to the axis of the support, the support having bearing surfaces spaced apart for engaging the under face of the floor, and the support being spaced apart from the floor 50 between the bearing faces, and means for shifting the floor, substantially as and for the purpose specified.

3. In a trap door for railway car platforms, a support movable about an axis and 55 comprising a body, and a leaf pivoted to the body and arranged with its pivotal axis extending crosswise of the axis of the body, a floor slidably mounted on the support and connected to the leaf by a pivot pin, the 60 support slidably engaging the under face of the floor and one of the slidably engaged parts being formed with raised bearing faces for engaging the other of said parts and the slidably engaged parts being spaced apart between the bearing faces, and means

for sliding the floor relatively to the support, substantially as and for the purpose set forth.

4. In a trap door for railway car platforms, a support movable about an axis and comprising a body, and a leaf pivoted to the body and arranged with its pivotal axis extending crosswise of the axis of the body, a floor slidably mounted on the support and being connected to the leaf by a pivot pin, the support being formed with raised bearing surfaces thereon spaced apart in a direction lengthwise of the axis thereof for engaging the under face of the floor, and the leaf being formed with a raised bearing face 70 near the pivot pin for engaging the under side of the floor, the remaining portion of the leaf being spaced apart from the under face of the floor, and means for sliding the floor relatively to the support, substantially 75 as and for the purpose described.

5. In a trap door for railway car platforms, a support movable about an axis and comprising a body, and a leaf pivoted to the body and arranged with its pivotal axis 80 extending crosswise of the axis of the body, and a floor slidably mounted on the support and connected to the free end of the leaf by a pivot pin, the support slidably engaging the under face of the floor and being provided with raised bearing faces for 85 engaging the under face of the floor, such bearing faces being located near opposite ends of the leaf, substantially as and for the purpose specified.

6. In a trap door for railway car platforms, a support movable about an axis and comprising a spring barrel provided with brackets spaced apart, and leaves pivoted to the brackets and arranged with their pivotal axes extending crosswise of the axis of the barrel, a floor slidably mounted on the support and being connected to the leaves near their ends by pin-and-slot connections, the support slidably engaging the under face of the floor and being provided with raised bearing surfaces located directly above and near the axis of the support at points spaced apart and near the ends of the leaves, and means for sliding the floor relatively to the support, substantially as and for the purpose specified.

7. In a trap door for railway car platforms, a support movable about an axis and including a body journaled in the car frame, a floor carried by the support and shiftable in a direction parallel to the axis of the support, the floor extending on opposite sides of the body, and means for shifting the floor, said means being connected to the part of the floor between the body and the end of the car, substantially as and for the purpose described.

8. In a trap door for railway car platforms, a support movable about an axis and

- including a body journaled in the car frame, a floor carried by the support and shiftable in a direction parallel to the axis of the support, the major part of the floor being located on one side of the axis of the body and a marginal portion thereof being located on the opposite side of such axis, and means for shifting the floor, said means being connected to said marginal portion of the floor, substantially as and for the purpose specified.
9. In a trap door for railway car platforms, a support movable about an axis and including a body journaled in the car frame, a floor carried by the support and shiftable in a direction parallel to the axis of the body, the major part of the floor being located on one side of the axis of the body, and a marginal portion of the floor extending to the opposite side of such axis, and means for shifting the floor, said means comprising a vertical rock shaft rising from the platform and extending below the same, the rock shaft having a rock arm at its lower end, and a link engaging the rock arm and said marginal portion of the floor, substantially as and for the purpose set forth.
10. The combination with a railway car platform, and the steps leading downwardly therefrom; of a trap door for normally covering the steps, the trap door comprising a support movable about an axis, and including a body journaled in the car frame, a floor carried by the support and shiftable in a direction parallel to the axis of the body, the major part of the floor extending on one side of such axis and a marginal portion thereof being located on the other side of such axis, and means for shifting the floor comprising a vertical rock shaft rising from the platform and extending below the same, the rock shaft having a rock arm at its lower end, and a link located beneath the platform and pivotally connected to the rock arm and to the under side of said marginal portion, the link extending through the riser of the top step of the platform, substantially as and for the purpose described.
11. In a trap door for railway car platforms, a support movable about the axis and comprising a body, and a floor slidably mounted on the support and having bearing members spaced apart and slidably engaging the body for guiding the floor in its sliding movement and securing the floor to the body, substantially as and for the purpose specified.
12. In a trap door for railway car platforms, a support movable about the axis and comprising a body in the form of a barrel, brackets mounted on the body, and leaves carried by the brackets, a floor slidably mounted on the support and connected to the leaves and members connected to the floor and co-operating with the body between the brackets and arranged to engage the brackets respectively for limiting the movement of the floor relatively to the body in opposite directions, substantially as and for the purpose set forth.
13. The combination with a railroad passenger car having a platform with a step opening therein, of a trap door for closing such opening, said door being shiftable in a lengthwise direction for projecting a portion thereof beyond the plane of the side of the car, and means for shifting the door comprising a vertical rock shaft rising from the car platform and having a part extending below the same, a rock arm associated with the lower end of the shaft, a link connected at one end to the outer end of said arm and at its other end to the door and a handle at the upper end of the shaft for rocking the same, substantially as and for the purpose described.

In testimony whereof, I have hereunto signed my name in the presence of two attesting witnesses, at Syracuse, in the county of Onondaga, in the State of New York, this 19th day of February, 1912.

ROY T. AXE.
